S. D. BAKER.

SOAP RECEPTACLE

APPLICATION FILED APR. 3, 1915.

1,239,076.

Patented Sept. 4, 1917.

~~Eng. of. 2~~

UNITED STATES PATENT OFFICE.

STEPHEN D. BAKER, OF NEW YORK, N. Y.

SOAP-RECEPTACLE.

1,239,076.

Specification of Letters Patent.

Patented Sept. 4, 1917.

Application filed April 8, 1915. Serial No. 19,026.

To all whom it may concern:

Be it known that I, STEPHEN D. BAKER, a citizen of the United States, residing at New York city, in the county of New York and 5 State of New York, have invented certain new and useful Improvements in Soap-Receptacles, of which the following is a specification.

My object is to provide a receptacle for 10 soap and the like toilet articles that may be built into the wall of a bath room as a permanent fixture and which shall be so constructed as to facilitate the mason's work in properly setting it in the wall, afford a neat 15 and attractive appearance when in place, be capable of being readily cleaned, and have ample supporting surface for the soap or other article without requiring its depth to be such that it may not be set in walls or 20 partitions of even the modern relatively thin construction.

In the accompanying drawing,

Figure 1 is a front elevation of the improved receptacle in place in a wall; 25 Fig. 2 shows the wall in section and the receptacle in plan;

Fig. 3 is a vertical sectional view, on a larger scale, of the receptacle and the wall, the front face of the receptacle being shown 30 in this case flush with the wall surface; and,

Fig. 4 is a view similar to Fig. 3, but showing the flange of the receptacle overlapping the surface of the wall.

Describing in detail the preferred form of 35 the invention shown in the drawing: The receptacle is formed of an integral piece of material such as china in the shape of a box-like structure. It includes a bottom wall *a*, a back wall *b*, a top wall *c* and two substantially planiform side walls *d*, an external continuous flange or rim *e* arranged in a vertical plane at the front or open side of the receptacle, and a lip *f* forming a forward extension of the bottom wall *a*.

Each of the several walls *a*, *b*, *c* and *d* is 45 of substantially uniform thickness throughout.

The two side walls *d* stand in vertical planes parallel with each other and are flat, substantially from top to bottom.

The bottom wall *a* with the extension thereof formed by the lip *f* constitutes a more or less shallow dished part of the receptacle; preferably on its upper or dished surface it has a plurality of soap supporting ribs *a'*, extending from the front por-

tion of the lip *f* to the rear of the wall *a*. The under side of the wall *a* is preferably flat for a suitable distance back from the flange *e*.

The back wall *b* is as to its lower part flat and stands in a vertical plane.

The top wall *c* is at its forward portion flat and horizontal, but as for the rearward portion thereof and the upper portion of the wall *b*, they follow a concave curve of a relatively large radius, as at *c'*.

The front edges of the walls *c* and *d* are in a vertical plane; the lip *f* projects forward beyond this plane.

Surrounding the walls *a*, *c* and *d* and with its front face flush with the plane last referred to is the continuous flange *e*; this is square in front elevation, and its back surface is formed as a channel *e'* extending continuously of said flange.

At the back the receptacle is formed with two upper and two lower right angular projections *g*; each upper and lower projection *g* is aligned with or forms a continuation 80 of one of the side walls *d*. Thus, in effect, the receptacle consists of the parallel upright rectangular sides *d*—*g*, a concavo-convex receiver-wall, *a*, *b* and *c*, opening laterally and joining said sides and having its 85 top and back portions merging together in a curve of relatively large radius, and a projecting frontal flange or rim extending around the margins of said sides and receiver-wall, the bottom of the receiver-wall 90 preferably projecting beyond the frontal flange or rim.

The receptacle may be set in the wall structure either as shown in Fig. 3, where the front surface of its flange *e* is flush 95 with the surface of the tiling *h* or the like superficial portion of the wall, or, as shown in Fig. 4, where the flange *e* overlaps the tiling *h*. In either case, it is secured in position by mortar or the like *i* placed around 100 that portion thereof which for a more or less distance back of the flange *e* is rectangular in a vertical section parallel with the front plane of the receptacle; its generally square shape and its flange respectively assist the mason in leveling up the receptacle and as a gage in truing the same in proper relation to the wall surface.

The angular projections *g* afford rests or supports for the receptacle at the back 110 thereof, they being shown in the present case as abutting the inside of the mortar or

other material forming the part of the wall structure next to an adjoining compartment.

By providing the groove *e*' in the back of the flange *e*, a lip is left on the back of the flange which may be planed off smooth to secure a perfect face to face contact with some opposed surface, such as that of the tiling *h*.

It will be apparent that the interior of

- 10 the receptacle is so formed as to permit the same to be readily cleaned; the difficulty of keeping the top of the inside clean is avoided by forming the top and back walls so that they merge into each other in a curve 15 of relatively large radius, and the dished or shallow concave form of the bottom wall and the absence of angles in the bottom portion of the inside of the receptacle makes it possible to readily remove the soap drainings.

By providing the projecting lip *f*, the bottom wall affords ample supporting surface for the soap without making the front-to-rear depth of the receptacle so great that it may not be set in a relatively thin wall, if not in the manner shown in Fig. 3, where its flange is flush with that of the wall surface, at least in the manner shown in Fig. 4, where its flange overlaps.

- 25 30 I do not wish to be limited to a receptacle for toilet articles in the exact form herein described and shown, nor specifically to be used as a fixture, what I claim being

1. A wall receptacle including, integrally

formed, a pair of spaced upright substantially rectangular sides, and a concavo-convex receiver-wall open laterally and joining said sides and forming top, bottom and back walls and having its top and back wall portions in part substantially flush with the top 40 and back edges of said sides, respectively, and thereupon merging into each other in a curve of relatively large radius.

2. A receptacle for toilet articles including, integrally formed, a box-like structure 45 having top, back, bottom and two side walls and being open for nearly its full height and width at the front, the bottom having a horizontal under bearing surface and being closed and shallow-concave and said receptacle having its back and top walls merging in a curve of relatively large radius, and a frontal vertical flange having said bottom, top and two side walls merging thereinto.

3. A receptacle for toilet articles including, integrally formed, a pair of spaced upright substantially rectangular sides, and a concavo-convex receiver-wall open laterally and joining said sides and forming top, bottom and back walls and having its top and back wall portions in part substantially flush with the top and back edges of said sides, respectively, and thereupon merging into each other in a curve of relatively large 60 radius.

In testimony whereof I affix my signature.

STEPHEN D. BAKER.
